CONSTRUCTION SHEET CARRIER OR SIMILAR ARTICLE

Fred C. Wagner, 905 N. 4th Ave.,
Yakima, Wash. 98902

Filed June 25, 1969, Ser. No. 17,875

Term of patent 14 years

Int. Cl. D8—02

U.S. Cl. D41—1

FIG. 1

FIG. 2

FIG. 3

FIGURE 1 is a left front perspective view of the construction sheet carrier or similar article embodying my new design;

FIGURE 2 is a rear elevational view thereof on a reduced scale;

FIGURE 3 is a right side elevational view thereof, the arm and construction sheet being shown in broken lines for illustrative purposes only.

I claim:

A construction sheet carrier or similar article, substantially as shown and described.
